5 SHEETS—SHEET 1.

This technical cross-sectional diagram illustrates a complex mechanical assembly, possibly a cylinder or pump, featuring a series of vertical components and a base with numbered circular labels. The assembly is labeled with various numbers, including:

- 0, 1, 2, 3, 4, 5, 6, 7, 8, 9 (Circular labels at the base)
- 2, 20, 21, 22, 23, 24, 25, 26, 27, 28, 29, 30, 31, 32, 33, 34, 35, 36, 37, 38, 39, 40, 41, 42, 43, 44, 45, 46, 47, 48, 49, 50, 51, 52, 53, 54, 55, 56, 57, 58, 59, 60, 61, 62, 63, 64, 65, 66, 67, 68, 69, 70, 71, 72, 73, 74, 75, 76, 77, 78, 79, 80, 81, 82, 83, 84, 85, 86, 87, 88, 89, 90 (Numerical labels throughout the diagram)

The diagram shows a series of vertical components, likely piston rods or valves, arranged in a stepped pattern. The base features a series of numbered circles (0-9) and a horizontal line with a vertical dimension line indicating height. The top of the assembly has a horizontal line with a vertical dimension line indicating height.

UNITED STATES PATENT OFFICE.

EDWARD L. DE FOREST, OF WESTHAMPTON, NEW YORK.

CALCULATING-MACHINE.

1,064,451.

Specification of Letters Patent. Patented June 10, 1913.

Application filed February 2, 1912. Serial No. 674,948.

To all whom it may concern:

Be it known that I, EDWARD L. DE FOREST, a citizen of the United States, residing at Westhampton, in the county of Suffolk and State of New York, have invented certain new and useful Improvements in Calculating-Machines, of which the following is a specification.

This invention relates to calculating machines and is directed to the provision of a machine of an improved construction whereby mathematical calculations may be performed rapidly, conveniently and accurately.

One of the primary objects of the invention is to provide a machine for multiplying so constructed that but a single operation is necessary in order to produce the result of the multiplication in the reading space of the machine. In this respect the invention is radically distinguished from machines of the type known as "key-set" machines employing slide-bars, wherein the slide-bars are positioned in accordance with the depression of keys of a key-board and thereafter an operating handle is operated as many times as the number by which it is desired to multiply the number set up upon the key-board of the machine. For instance, in a machine of this type when used for multiplying by the digit 9, it would be necessary to move the operating handle nine times, thereby adding the number set up upon the key-board of the machine nine times. In accordance with the present invention, however, the method of procedure is radically different. The operating handle or key is moved but once to multiply by a single number and in such movement it actuates suitable parts so that the product obtained by the multiplication may be read at once.

While one of the principal features of the invention resides in the construction whereby multiplication can be effected in the manner above indicated, the machine may also be used for performing calculations in addition and subtraction, and therefore I do not wish to be limited as to the character of the operations for which the principles of my invention are utilized.

I have illustrated an embodiment of my invention in the accompanying drawings in which—

Figure 1 is a plan view of the machine with the casing removed and broken away in

part, Fig. 2 is a transverse section of the machine on lines 2—2 of Figs. 1 and 3, Fig. 2^a is a top view of a portion of the mechanism shown in Fig. 2, Fig. 3 is a front view of the machine broken away and sectioned in part, Fig. 4 is a view partly in horizontal section and partly in plan showing the number-wheels, Fig. 5 is a detail sectional elevation on line 5—5 of Fig. 4, Figs. 6 and 7 are detail views showing a portion of the mechanism shown in Fig. 4, Fig. 8 is a sectional detail view hereinafter referred to, Fig. 9 is a sectional detail view illustrating a modification of the construction shown in the preceding figures, Fig. 10 is a plan view of a portion of the mechanism shown in Fig. 9, Fig. 11 is a detail elevation showing a portion of the mechanism shown in Fig. 9, Fig. 12 is a sectional detail view on line 12—12 of Fig. 9, Fig. 13 is a sectional view of a portion of the mechanism shown in Fig. 9 and Fig. 14 is a detail view of the escapement for the carriage.

Referring first to Figs. 1 to 8 inclusive, a shaft is shown at 1 (Figs. 1 and 3) which shaft is rotated on the depression of any key of the key-board to an extent commensurate with the value of the key depressed. The key-board mechanism is arranged in any suitable manner to effect this result. In the drawings I have shown a form of key-board mechanism for operating in this way, but it will be understood that the construction shown is illustrative only and may be modified in any respect desired for use in connection with parts operating in accordance with my invention. In the construction illustrated, a row of keys is provided, these keys being numbered from zero to nine inclusive. Each key 2 is normally held elevated in the position in which it is shown in Fig. 3 by a spring 3. The keys have a definite range of movement downwardly against the tension of the springs 3, which downward movement being arrested in any suitable manner, as for instance, by the engagement of the key with the support for the keys. Below the support the key-stems 4 are of varying length, the stem of the key number "nine" being the longest and the others being of progressively decreasing length. The lower end of each key-stem is adapted to engage and operate a universal bar 5 (Fig. 3). This bar is mounted at op-

posite ends so as to have a parallel motion. Its ends are shown as pivotally connected to the free ends of levers 6 which are pivotally mounted upon the frame of the instrument. 5 A spring 7 acts upon one of the levers 6 to normally hold the bar 5 in its upper position. Pivotally mounted upon the bar 5 is a rack-lever 8 which is held by a spring 9 in engagement with teeth on a ratchet-wheel 10 secured upon a stub-shaft 11. This stub-shaft is mounted for rotation in a bearing formed in the frame of the machine and has secured thereto a gear-wheel 12. This gear meshes with a pinion 13 rigidly secured upon the shaft 1. The shaft 1 is mounted for rotation in bearings formed in frame-members 14 and similar shafts 15, 16, 17, etc., are arranged parallel to the shaft 1 for rotation in bearings similarly provided. A 15 gear 18 is splined upon the shaft 1, the shaft being preferably of square cross-section and fitting snugly in a square opening extending through the gear. The gear 18 has secured thereto a member 19 provided 20 with a circumferential groove in which a finger 20 is received. This finger is adapted to be moved by an operating handle 21 projecting downwardly through the casing of the machine. When the gear 18 is in the 25 position in which it is shown in Fig. 1, it meshes with an idler-gear 22 mounted on a stub-shaft carried by the frame-plate 14 and this idler-gear meshes at all times with the gear 23 secured upon the shaft 15. When 30 handle 21 is operated, the finger 20 moves the member 19 and the gear 18 axially upon shaft 1 so that the gear 18 is out of mesh with the idler 22. The shafts 15, 16 and 17 are geared together by means of idler-gears 35 35 22 and gears 23 on the several shafts in the manner above described. On each of the shafts 1, 15, 16 and 17 is splined a cylindrical setting member 24 provided with nine projecting fingers 25, the nine fingers being 40 arranged spirally upon the surface of the member 24 as they are shown in Figs. 1 and 2. At one end the member 24 is provided with a circumferential groove adapted to receive studs 26 upon a yoke 27. This yoke 45 is secured to an operating arm 28 (Fig. 2) whose head projects upwardly through a slot in the casing of the instrument in the manner shown in Fig. 2a. A member 24 having spiral projections 25 thereon is provided upon each of the shafts 1, 15, 16, 17, etc., and each of these members 24 is provided with an operating arm 28 whereby the member may be moved axially upon the shaft on which it is splined. Each of the 50 slots in the casing of the instrument through which the head of an arm 28 projects is provided with numbers along its edge from zero to nine inclusive. Directly below each of the shafts 1, 15, 16, 17, etc., is a rod 29 (Figs. 55 2 and 3) which rod serves as a pivotal sup-

port for nine pawl-carrying arms 30. Each pawl-carrying arm 30 is normally held in the position in which it is shown in Fig. 3 by a spring 31, the movement of the arm affected by the spring being arrested by a suitable stop-rod 32. Near its free end each arm 30 has a pawl 33 pivotally mounted thereon and actuated by a spring 34 to hold it in contact with the part operated thereby. The extreme ends of the arms 30 are adapted 70 to be engaged by the projections 25 on the arms 24. Adjacent to each shaft 1, 15, 16, 17, etc., is a shaft 35 (Figs. 1 and 3) mounted for rotation in bearings formed in the frame-plates 14. On each of the several 75 shafts 35 is a ratchet-wheel 36 elongated in the direction of the axis of shaft 35 so that the nine pawls 33 upon the nine arms 30 may coact therewith. 80 With the construction above described it 85 will be seen that when any one of the keys of the key-board is depressed, the shaft 1 will be rotated to an amount commensurate with that key. The gearing is so proportioned that on the depression of any key 90 the shaft 1 will make a number of revolutions equal to the value of the depressed key. If the setting member 24 upon shaft 1 be moved axially upon the shaft by means of 95 its handle 28 until the index on that handle points to the number "1" adjacent to the slot for the handle, then when the member 24 is rotated by the rotation of shaft 1, only one of the projections 25 on the member 24 will engage a pawl-carrying arm 30, and therefore the ratchet 36 secured on shaft 35, 100 will be actuated one step or a distance equal to one tooth of the ratchet during each revolution of shaft 1. In other words, if the member 24 on shaft 1 be moved to the position corresponding to the number "1" and the "nine" key in the key-board be then depressed, the shaft 1 will be caused to make nine complete revolutions; each time it makes a revolution, one projection 25 on 105 arm 24 will engage a corresponding arm 30 and actuate that arm against the tension of its spring 31 and cause the pawl 33 carried by arm 30 to actuate the corresponding ratchet 36 one step. If, on the other hand, 110 the member 24 had been moved through its full range so that the index upon its operating arm pointed to the figure "9" on the 115 scale adjacent to the slot in the casing for that operating arm, then when the "9" key was depressed to cause nine revolutions of the shaft 1, all of the projecting fingers 25 upon the cylinder 24 would engage the upper ends of the arms 30 one after the other and the coaction of each finger 25 with an arm 30 would cause the ratchet-wheel 36 to be moved around one step so that the shaft 35 would be rotated a total of eighty-one steps. When the idler-gear 22 is in the 120 multiplying position in which it is shown, 125 i30

in Fig. 1, the rotation of shaft 1 will be communicated to shafts 15, 16 and 17. If the setting members or cylinders 24 on shafts 15, 16 and 17 have been positioned in accordance with the digits of the multiplicand, then when a key of the key-board corresponding to a digit of the multiplier is depressed, the rotational movement which, as above described, is given to shaft 1 is communicated to the shafts 15, 16 and 17 and the members 24 on the latter shafts cause the ratchets 36 corresponding thereto to be actuated a number of steps commensurate with the product of the multiplier and the appropriate digit of the multiplicand.

Each of the shafts 35 has a bevel gear 37 (Figs. 1, 2 and 8) secured upon the rear end thereof. Each of these bevel gears is adapted to mesh with and to drive either one of two bevel gears 38 and 39 upon a sleeve 40 which is rotatable upon a shaft 41 extending transversely of the machine. The sleeve 40 is held against axial movement upon shaft 41 by collars 42. A pinion 43 is secured upon sleeve 40 adjacent to the bevel gear 38. Normally, that is when the machine is used for either addition or multiplication, the several gears 38 mesh with their respective gears 37 and the gears 39 are out of mesh with their respective gears 37 as shown in Fig. 1. When it is desired to use the machine for operations in subtraction the gears 38 and 39 are moved axially so as to carry the gears 39 into mesh with the gears 37 and the gears 38 out of mesh with the gears 37. This is effected by means of an operating lever 44 which is pivotally mounted upon the frame of the machine and at its rear end is bifurcated, the bifurcated ends 40 extending into a circumferential groove formed in a member 45 which is secured upon shaft 41. When lever 44 is moved about its pivot it moves the shaft 41 in the direction of its axis and the shaft carries with it the several sleeves 40 each with a pair of gears 38 and 39 secured thereon. This having been done, rotation of any shaft 35 will cause rotation of the sleeves 40 corresponding thereto, in a direction opposite to that in which the sleeve was rotated by shaft 35 when the gear 38 was in mesh with the gear 37.

Each of the pinions 43 meshes normally with a gear 46 and all of the gears 46 are loosely mounted upon a shaft 47 which is suitably supported in a carriage 48. This carriage is mounted for movement transversely of the machine upon rods 49 which pass through openings 50 in the carriage 48. A spring or other driving device shown diagrammatically at 51 in Fig. 1 moves the carriage to the right as shown in Fig. 1, in a manner similar to the transverse movements of a type-writer carriage. The movement of the carriage is governed by an

escapement such as that shown in Fig. 14. Referring to the latter figure it will be seen that frame 48 has a stop-bar 52 secured to the lower edge thereof. With this bar contacts a pallet 53 pivotally mounted at 54 and actuated in one direction by a spring 55. A depending arm of this pallet is adapted to be engaged and raised by the inner end of a lever 56 (Fig. 2). This lever is pivotally mounted upon the base of the instrument and at its forward end is pivotally connected by a link 57 to a lever 58, the latter being pivotally mounted upon an ear projecting from the frame of the instrument. The forward end of the lever 58 is provided with a stop-tooth 60 which normally projects under the bar 5. When the bar 5 is depressed the stop-tooth 60 is turned on its pivot against the tension of its spring but the lever 58 is not moved thereby. On a return movement of the universal bar 5 actuated by its spring, the bar engages the stop-tooth 60 and raises it, and since that tooth may not be raised without actuating the lever 58, the latter is turned about its pivot and thereby rocks the lever 56 whose rear end engages the depending end of the pallet 53 and rocks the latter against the tension of its spring. This carries the tooth of the pallet out of engagement with the tooth of the stop-bar 52 and a lateral projection 61 of the pallet engages the stop-bar 52 so as to retard the movement of the carriage. The carriage being released by the pallet 53, is moved by its spring 51 upon the rods 49 until the next tooth of the stop-bar 52 comes into engagement with the tooth of the pallet 53 whereupon movement of the carriage is arrested. The movement of the carriage in this way carries all of the gears 46 one step to the right so that each gear 46 is carried out of engagement with the pinion 43 with which it had been in mesh and the next wheel 46 to the left is carried into mesh with that pinion.

Referring now to Figs. 1 and 4 to 7, it will be seen that the gear 46 at the right has a cylinder 62 secured thereto or formed integral therewith and that on the exterior surface of this cylinder are printed one or more series of numbers from zero to 9 inclusive. The side face of the member constituting the gear 46 and number-wheel 62 is formed to constitute a cam for effecting the carrying from one denomination to the next higher one. This cam is provided with one raised portion for each series of numbers from zero to 9 upon the surface of the number-wheel. One of these raised portions is shown at 63 in Fig. 4. On an arm projecting from the frame of the carriage is pivotally mounted a lever 64 whose outer end is adapted to engage and be operated by the cam projections 63. A spring 65 acts upon the lever 64 to hold its end at all

times in engagement with the cam. The end of lever 64 opposite that which bears upon cam 63 is bifurcated and each of the bifurcated ends is connected by a link 66 to one end of a link 67 whose opposite end is pivotally connected to one end of a rod 68. The pivot-pins connecting the links 67 to the rods 68 are extended and enter slots 69, between pieces secured to the frame of the carriage so that the rods 68 are caused to move in a straight line. At their outer ends the two rods 68 are supported upon a strip 69 in the manner indicated in Fig. 5, the rods 68 being provided with lengthwise slots through which extend screws 70 whose ends enter the strip 69. Each of the rods 68 carries a pawl 71. The second gear 46 from the right hand side of the machine is provided, as shown in Fig. 4, with a number-bearing surface 62 and a cam 63. A shield 72 is provided for the number-bearing surface 62 of this wheel, this shield having a cylindrical portion which incloses the portion 62 and which is provided with an opening large enough to disclose one number upon the surface 62. The shield 72 is carried by a sleeve 73 (Figs. 4, 6 and 7) which sleeve is axially movable upon a sleeve 74 on shaft 47. Sleeve 73, however, cannot rotate relatively to sleeve 74 as a screw 75 passes through a slot in the sleeve 73 and enters the sleeve 74. This screw 75 passes through the hub of a pinion 76. The three members 76, 73 and 74 are therefore caused to rotate in unison but sleeve 73 can at any time move axially with respect to sleeve 74 and pinion 76. The sleeve 73 serves as a support for a member 77 which is secured thereon and which is provided with a circumferential groove. Sleeve 74 is a spacer for adjacent gears 46 and additionally holds the gears 76 against axial movement. The sleeve 73 transmits the axial movement of shields 72 to the member 77. This movement of shield 72 is effected by the cam projections on the cam 63 which are engaged by rollers 78 secured to the interior of the shield, there being one cam projection or one pair of diametrically-opposite cam projections on cam 63 for each series of numbers on the surface 62. The gear 76 is engaged and operated by the pawl 71 as above described and when it does so move it carries with it the sleeve 73 and shield 72.

The parts so far described serve to carry over from the lowest denomination to the next higher one. A stationary shield 79 is provided inclosing or partially inclosing the portion 62 of the first wheel 46 having the numbers thereon and in this shield is an opening disclosing one number only. When the rotation of this wheel carries the "9" past the opening in the shield, a projection 63 actuates lever 64 which in turn operates

through links 66 and 67 to reciprocate the strips 69. This causes the pawl 71 on one of the strips 69 to actuate the gear 76 adjacent to the second wheel 46, that is, the wheel of the next higher denomination, and the pawl actuates gear 76 a distance equal to one tooth of that gear. In so rotating, gear 76 carries with it the shield 72 and the shield is thus moved so that it discloses the number next higher or next lower than the one which had previously been disclosed through the opening in the shield. The carrying of the tens from the lowest denominational wheel to the next higher wheel is thus effected. In carrying from the second wheel to the third one, the construction is slightly different but the operation is substantially the same. When the second wheel is turned, either by the carrying mechanism heretofore described, or by the pinion 43 meshing with that gear 46 so as to carry the "9" on the number-surface of the wheel past the opening in the shield 72, the projection or projections on the cam surface 63 engage the roller or rollers 78 and move the shield axially a short distance and then permit it to return to its former position under the stress of a spring 80. This axial movement of shield 72 carries with it the sleeve 73 and member 77. The circumferential groove in the member 77 receives studs on the bifurcated ends of a lever 81 which is similar in a general way to the lever 64. This lever 81 is mounted for rocking-movement upon a rod 82 carried by arms projecting from the frame 48 of the carriage. At its end distant from the member 77 it is bifurcated and each of the bifurcated ends is connected by links 66 and 67 to pawl-carrying rods 68 similar to those shown in Fig. 5 and above described. By means of these connecting members, the axial movement of shield 72 is caused to actuate the pawl-carrying rods 68 which operate the gear 76 corresponding to the wheel of the next higher denomination so that the carrying over is properly effected. When shield 72 and sleeve 73 move axially thus, they in no way affect the position of the gear 76 mounted on the sleeve 73, as the gear 76 is held from axial movement by its connection to the sleeve 74 through the pin 75.

As heretofore stated, the outer ends of each pair of rods 68 are supported by a strip 69 and all of the several strips 69 are suspended from a rod 83 (Fig. 5) extending between suitable supports upon the frame of the carriage. The strips 69 are all provided with slots in their upper ends through which the rod 83 extends. The lower ends of the strips 69 have extensions 84 thereon which pass through openings in a bar 85 forming part of the frame of the carriage. Each of these extensions has a spring coiled thereon and under compression between the 130

bar 85 and a nut on the extension 84. The upper end of each strip 69 is turned at a right angle as shown at 86 and this bent portion of each strip is adapted to be engaged by a cam 87 secured on the rod 83 which rod is adapted to have a rocking movement in the bearings which support it. At its end rod 83 is provided with an operating handle as shown at 88 in Fig. 2. With the parts in the positions in which they are shown in Fig. 5, the pawl 71 on the upper rod 68 is in coaction with the gear 76 but the pawl on the lower rod 68 is out of coaction with gear 76. This may be the position of the parts when the machine is used for subtraction. By turning handle 88, the cams 87 may be turned through substantially 90 degrees and in so turning they will raise the several strips 69 which will carry with them the outer ends of the several pairs of rods 68. This will carry the pawls 71 on the upper rods 68 out of coaction with gears 76 and the pawls on the lower rods 68 into coaction with those gears so as to adapt the machine for addition or multiplication. When the strips 69 and rods 68 are so raised they will be held by the cams 87, or, if desired, an impositive stop 89 (Fig. 5) may be provided for holding the strips 69 so raised. The operation of the machine has been described in connection with the foregoing description of the construction employed. If it be desired to use the machine for addition, the handles 21 and 88 are moved to the proper positions and the cylinder 24 on the rod 1 is moved forward until its operating handle is at the position marked "1". When so positioned, the first projection 25 on cylinder 24 will be in position to engage a pawl-carrying arm 30 but no other projection 25 will be in position to actuate a pawl-carrying arm. If a key of the keyboard be depressed the shaft 1 will be rotated a number of revolutions equal to the value of the key depressed but the shafts 15, 16, etc., will not be rotated as the gear 18 is out of mesh with the first idler-gear 22. As shaft 1 is so rotated, the rear-most pawl-carrying arm 30 is actuated once during each revolution of shaft 1 and when so actuated, turns the ratchet wheel 36 and the shaft 35 on which it is mounted one step. The shaft 35 is thus advanced a number of steps equal to the value of the key depressed. This rotational movement is communicated by the gears 37, 38 and 43 to the gear 46 so that the gear 46 is advanced an amount commensurate with the value of the key depressed. If at the beginning of the operation the "0" on the number surface 62 had shown through the opening in the shield 79, then after the depression of the key the number on the surface 62 corresponding to the number on the key depressed would 65 show through the opening in shield 79. As

the key is raised after being released, it actuates the escapement mechanism through the parts 60, 58, 57 and 56 (Fig. 2) and allows the carriage with all the number-wheels thereon to move one step to the right. This brings the next wheel 46 into mesh with the first pinion 43 and the second digit from the right of the number which is to be registered may be registered by the depression of the key corresponding thereto. In this way the whole number may be set up and the carriage moved to the right one step after each key is depressed. The carriage may then be returned manually to its initial position with the first wheel in mesh with the first gear 43. The next number to be added may then be registered. If in registering any digit of the second number, the total of that digit and the number previously registered upon the wheel which is then in mesh with the pinion 43 exceed ten, then the carrying mechanism will operate in the manner above described carrying over one to the next higher denomination.

If it be desired to use the machine for subtraction, the handle 21 and the several operating levers 28 are left in the position to which they have been moved for addition and the handles 44 and 88 are operated. Movement of handle 44 carries the gears 38 out of mesh with the gears 37 and the gears 39 into mesh with the gears 37 so that the rotation of shaft 35 will cause rotation of the number-wheels in the opposite direction. Also, by reason of the shifting of the several pairs of rods 68, the lower pawls 71 will be carried out of coaction with the gears 76 and the upper pawls 71 will be carried into coaction with the gears 76 so that the carrying mechanism will operate to cause reverse rotation of the several number-wheels. The operation is then proceeded with in the manner heretofore described in connection with the operation of addition.

To adapt the machine for multiplying, the handles 44 and 88 are moved to the positions which they occupy when using the machine for addition and the handle 21 is moved to the position which carries gear 18 into mesh with the first idler 22. The multiplicand is then set up by moving the handles 28 and with them the cylinders 24 forwardly to the positions corresponding to the digits of the number constituting the multiplicand. The digit at the right of the multiplier is then registered by depressing the key appropriate thereto. On such depression, the shafts 1, 15, 16, 17, etc., are caused to rotate through a number of revolutions equal to the value of the key depressed and in so doing each of these shafts causes rotation of the adjacent shaft 35 commensurate with the product of the number on the de-

pressed key and the number registered by the movement of the corresponding cylinder 24 and operating handle 28. That is, if the first cylinder 24 had been moved by its operating handle 28 to the "9" position, and the "9" key had been depressed, then the first shaft 35 would be caused to rotate a distance equal to 81 steps of the movement communicated to the shaft by the pawls 33 and the ratchet 36. As the several shafts 35 rotate thus commensurate with the product of the multiplicand and the first digit of the multiplier, each shaft causes rotation of the number-wheel corresponding thereto through the gearing 37, 38 and 43. Except for the necessity of carrying tens to the next higher denomination, this operation would result in displaying the product of the multiplication by the number-bearing surfaces of the several number-wheels as seen through the openings in the shields. The carrying is effected by moving the shields one step at a time as may be required by the carrying operation in a direction opposite to that in which the number-wheels are moved. Thus, as the first wheel is rotated, each time the "9" thereon passes beyond the opening in the corresponding shield, the carrying mechanism operates, as above described, to turn the shield of the next adjacent number-wheel one step in a direction opposite to that in which the number-wheel corresponding thereto is moved. The whole operation therefore results in giving the product of the multiplication by displaying the digits making up this product through the openings in the several shields of the number-wheels. After the return of the key to its normal position, the carriage moves one step to the right and each number-wheel thereon is carried into engagement with the gear 43 which previously had been engaged by the next number-wheel to the right. The key is then selected which corresponds to the second digit from the right of the multiplier and this key is depressed, resulting in actuation of the number-wheels in the manner before described. By reason of the shifting of the carriage one step to the right, the parts will be in position for registering the multiplication of the multiplicand by the second digit from the right of the multiplier. The operation proceeds in this way until the final product is obtained.

Using the construction above described, the digits constituting the product would not be in line across the machine. The facility with which the product may be read, even though the digits thereof are not in line across the machine, may be increased by placing upon each number-wheel several series of numbers from zero to nine. For instance, three such series of numbers may follow each other around each number-wheel. In such case, the casing of the ma-

chine would be so formed as to allow only one-third of the circumference of each shield to show through a slot therein. Each shield would, of course, be provided with three sight openings therethrough, and three cam projections, or pairs of cam-projections would be provided on each number-wheel for actuating the carrying mechanism.

The machine may be provided with any suitable mechanism for effecting a return of the number-wheels to the zero position.

In Figs. 9 to 13 inclusive, I have illustrated a modification of the construction above described. The principal difference between this construction and the one shown in Figs. 1 to 8 is that the product of a multiplication is displayed by the number-wheels with the digits thereof in line across the machine. Figs. 9 to 13 show a modified construction of the carriage and the carrying mechanism. Each of the shafts 35, other than the one at the right, which shafts are each rotated a number of steps commensurate with the product of a multiplication, is extended back through its rear bearing and on its rear end carries an arm 90 on which two spring-actuated pawls 91 and 92 are mounted. These pawls engage ratchet wheels 93 and 94 respectively. The two ratchet wheels are carried by a shaft 95 and one of the wheels 94 has a gear 96 formed integral therewith. The gear 96 meshes with a gear 98 which is formed integral with a bevel-gear 99. This gear may mesh with either of two bevel gears 100 and 101 secured upon a sleeve 102 which is loose on a shaft 97 and which carries a spur-gear 103. Means are provided for holding the ratchet wheels 93 and 94 against movement axially upon or with the shaft 95. Any suitable mechanism may be employed for this purpose. In the drawings I have shown each pawl 91 and 92 as provided with extensions 121 which embrace the corresponding ratchet wheel and in that way prevent axial movement of the wheel while permitting rotational movement thereof. The shaft 95 is supported at one end by a pin 114 on the end of shaft 35 which pin enters an axial opening in the end of shaft 95. A spring 115 is coiled about pin 114 between the ends of shafts 35 and 95. The opposite end of shaft 95 is supported by and passes through a bearing 122. This shaft is provided with two inclined or spirally arranged slots or grooves 116 and 117 therein, the two grooves being oppositely inclined. The ratchet-wheel 93 has a pin 118 thereon entering the groove 116 and the ratchet-wheel 94 has a pin 119 thereon entering the groove 117. For the first shaft 35 at the right of the machine, it is unnecessary to provide ratchet wheels 93 and 94 and an axially movable shaft 95 as it is unnecessary to provide a carrying mechanism which carries to this shaft 35.

Instead, this shaft at the right of the machine may be extended backwardly, as indicated in Fig. 10, and may carry on its rear end a gear 96 which engages with and drives the gear 98. For all of the other shafts 35, however, a construction such as that illustrated in Fig. 9 is provided. The carriage is shown at 123, it being arranged for transverse movement upon rods 49; as heretofore described. On the frame of the carriage is mounted a shaft 106 which forms support for a plurality of number-wheels 107 each of which is secured to a gear 105. Each gear 105 meshes with a gear 104 carried by a shaft 108 which is mounted on the frame of the carriage. The gear 104 is secured on a sleeve 120 which has a cam 109 secured thereon. The sleeve 120 is held against movement axially on shaft 108 by collars 124. The gear 104 on the carriage meshes with the gear 103 above referred to, and as the carriage is stepped along transversely of the machine, the gear 104 moves from one gear 103 to the next, step by step. A gear 104 with its coöperating cam 109 and a number-wheel 107 driven by the gear 104 are provided on the carriage for each numerical order. In coöperation with each cam 109 devices are provided on the carriage for operating the mechanism of the denominational order next higher than that one which drives the gear 104 corresponding to that cam 109. Mounted upon the carriage in position for coactuation with each cam 109 are two levers 110 and 111. Each of these levers is connected by a link 112 with a member 113 movable upon the frame of the carriage and adapted to engage the end of a shaft 95. It will be noted that the link 112 is connected to the lever 110 above the pivot of that lever and the other link 112 is connected to the lever 111 below the pivot of that lever. The upper ends of these two levers are engaged and operated by the cam 109 but the cam can operate only one of these two levers when in either one of its operative positions.

With the construction illustrated in Figs. 9 to 13, when the shafts 35 are actuated in the manner heretofore described, the rotation of each shaft 35 is transmitted to the number-wheel 107 corresponding therewith through the arm 90, pawl 92, ratchet 94, gears 96, 98, 99, 100, 103, 104 and 105. When any number-wheel passes from the "9" to the zero position thereon, the cam 109, turning with that number-wheel, actuates one of the levers 110 and 111. Assuming that cam 109 be in position on shaft 108 for coöperation with lever 110, the projection on the cam will move lever 110 about the pivot of the latter and will act through the link 110 to move the member 113 toward the shaft 95. The member 113 when so moved engages the end of shaft 95 and

moves that shaft against the tension of spring 115. As the shaft 95 is so moved the pins 118 and 119 are caused to travel in the slots 116 and 117. The arrangement of these parts is such, that when shaft 95 is so moved, the inclination of slot 116 tends to turn the gear 93 backwardly. Such turning movement of gear 93, however, is precluded by the pawl 91 and therefore, instead of gear 93 being moved backwardly, the shaft 95 is moved forwardly. The shaft 95 when so moved carries the gear 94 with it. Additionally, the gear 94 is rotated forwardly upon shaft 95 by the movement of pin 119 in the inclined slot 117. The total effect of the movement of shaft 95 relatively to gear 93 carrying the gear 94 with it, and the movement of gear 94 on shaft 95, caused by the two inclined slots, is to advance the gear 94 one step. This movement of one step is transmitted to the number-wheel 107 by the gearing actuated by gear 96. Immediately after the cam 109 releases the lever 110, the latter and the parts actuated thereby including the shaft 95, are moved back to their normal positions by the spring 115. As this occurs the movement of the pin 119 in the slot 117 tends to cause reverse rotation of the ratchet 94 but such rotation of ratchet 94 is precluded by the pawl 92. Therefore, instead of the gear 94 being rotated, the shaft 95 is rotated carrying with it the gear 93, the latter rotating in the forward direction, and additionally the gear 93 is caused to rotate upon shaft 95 by the inclined slot 116. This movement of the gear 93 is effected without in any way operating the gear leading to the number-wheel 107. Preferably, a spring 125 is provided for returning lever 110 and member 113 to normal position independently of the spring 115. Thus each time the number-wheel actuated by one shaft 35 passes from the nine to the zero position, it operates through the cam 109 corresponding thereto and the link 110 and member 113 actuated by that cam, to impart an additional impulse to the gearing for driving the number-wheel of the next higher order. This is effected by causing axial movement of the short shaft 95 forward and back and thus causing the ratchet 94 and gear 96 to move forward one step, that is a distance sufficient to cause the number-wheel driven thereby to turn a distance represented by one number thereon. When the shaft 95 is moved forward, it turns ratchet 94, but as it moves back, the ratchet is held by its pawl and the ratchet 93 only is moved. This ratchet, however, is not connected in the train of gearing leading to a number-wheel. Each number-wheel 107 has a cam 109 associated therewith except the last one at the left of the machine and for each cam 109 there is a member 113 actuated by links 110 and 111 which are engaged by the cam. 130

During the operation of the machine the carriage is moved to the right, step by step, as heretofore described. Each step movement of the carriage carries the several members 113 from positions opposite certain shafts 95 to positions opposite the next shafts to the right. To adapt the machine for operations in subtraction instead of addition or multiplication, the shafts 91 and 108 are moved axially a short distance in their bearings on the carriage, carrying with them the gears 100, 101, 103 and 104 and cams 109. This carries gears 100 out of mesh with gears 99 and gears 101 into mesh with gears 99. Also, this movement carries all the cams 109 out of coaction with the levers 110 and into coaction with the levers 111. The shafting of the gears thus reverses the direction in which the number-wheels are driven by the shafts 35. This reverses the direction in which the cam 109 is driven but the cam is in position for coaction with a lever which is inclined at the angle appropriate for operation by the cam. If desired, a lever may be employed in place of the levers 110 and 111 which will be operated by cam 109 when the latter is rotating in either direction. Thus a bell-crank lever may be employed having a horizontal area carrying a roller engaged by the cam. The opposite end of the bell-crank would be arranged to move shaft 95 in any suitable manner.

Having described my invention, what I claim as new therein and desire to secure by Letters Patent of the United States is:

- 35 1. A calculating machine comprising the combination of a plurality of independently movable setting devices which may be independently positioned simultaneously to represent a number consisting of a plurality of digits and constituting a multiplicand, a series of depressible number-keys, a series of number-wheels, and means operated by the depression of any one of the number-keys for operating the number-wheels to position them in accordance with the product of said multiplicand consisting of a plurality of digits and the value of the depressed key.
- 40 2. A calculating machine comprising the combination of movable setting devices which may be independently positioned simultaneously to register a number consisting of a plurality of digits and constituting a multiplicand, a plurality of depressible keys, a plurality of number-wheels, carrying mechanism for carrying from one number-wheel to the wheel of next higher denomination and means operated by the depression of any one of said keys for operating the number-wheels to position them in accordance with the product of said multiplicand consisting of a plurality of digits and the value of the depressed key.
- 45 3. A calculating machine comprising the

combination of setting means for setting up a number consisting of a plurality of digits, a plurality of number-wheels, a plurality of keys, and means actuated by a single depression of a key for actuating said wheels to cause them to indicate the product of said number consisting of a plurality of digits and the number of the key depressed, substantially as set forth.

4. A calculating machine comprising the combination of means for setting up a number consisting of a plurality of digits, a plurality of number-wheels, an operating device and means actuated by a single operation of the operating device for actuating the number-wheels to cause them to indicate the product of said number consisting of a plurality of digits and another number, substantially as set forth.

5. A calculating machine comprising the combination of a plurality of independently movable setting devices which may be independently positioned simultaneously to represent a number consisting of a plurality of digits and constituting a multiplicand, a series of depressible number-keys, a series of number-wheels, a movable carriage on which the number-wheels are mounted, means operated by the depression of any one of the number-keys for operating the number-wheels in accordance with the product of said multiplicand consisting of a plurality of digits and the value of the depressed key, and means controlled by the depression of a number-key for causing movement of said carriage.

6. A calculating machine comprising the combination of a plurality of independently movable setting devices which may be independently positioned simultaneously so as to represent a number consisting of a plurality of digits, a series of number-keys, a plurality of number-wheels, and means operated by any one of said number-keys for actuating the number-wheels to indicate the product of the number consisting of the plurality of digits represented by said setting devices and the number represented by the key operated, substantially as set forth.

7. A calculating machine comprising the combination of a plurality of keys, a plurality of shafts, means for operating said shafts amounts dependent upon the value of selected keys, a movable setting device in the connection from said means to said shafts and controlling the extent of operation of said shafts when actuated by said means, and a plurality of number-wheels connected to said shafts, substantially as set forth.

8. A calculating machine comprising the combination of a plurality of keys, a plurality of shafts, means actuated by the depression of any key for actuating one of said shafts, a setting device movable to any position and determining by its position the

- extent of actuation of a shaft when a key is depressed, and a number-wheel actuated by each of said shafts, substantially as set forth.
9. A calculating machine comprising the combination of a plurality of keys, a plurality of shafts, means actuated by the depression of any key for actuating one of said shafts, a setting device movable to any position and determining by its position the extent of actuation of a shaft when a key is depressed, a number-wheel actuated by each of said shafts and carrying mechanism between said number wheels, substantially as set forth.
10. A calculating machine comprising the combination of a shaft, an operating device for rotating said shaft, a setting member on said shaft and movable to various positions, a second shaft operated when said first-named shaft is rotated in accordance with the rotation of the first-named shaft and the position of said setting member, and a number-wheel actuated by said second shaft, substantially as set forth.
11. A calculating machine comprising the combination of a shaft, a row of keys, means actuated by the depression of any key for rotating said shaft, a setting member on said shaft and movable to various positions, a second shaft operated when said first-named shaft is rotated in accordance with the rotation of the first-named shaft and the position of said setting member, and a number-wheel actuated by said second shaft, substantially as set forth.
12. A calculating machine comprising the combination of a plurality of shafts, a number wheel connected to each of said shafts, carrying mechanism between said number wheels, an operating device, and means actuated by the operating device for operating all of said shafts simultaneously independently of the carrying mechanism, substantially as set forth.
13. A calculating machine comprising the combination of a plurality of shafts, a plurality of keys for selecting a number, a plurality of setting devices which may be positioned simultaneously for selecting a second number consisting of a plurality of digits, means for operating said shafts in accordance with the product of the numbers so selected, and a number wheel connected to each of said shafts, substantially as described.
14. A calculating machine comprising the combination of a plurality of shafts, a number wheel connected to each shaft, carrying mechanism between said number wheels, a plurality of keys, means actuated by the depression of any key for actuating all of said shafts independently of the carrying mechanism, and setting devices movable to control the operation of said shafts by said keys.
15. A calculating machine comprising the combination of a shaft, a plurality of keys, means for rotating said shaft in accordance with the value of a selected key, a second shaft, selective means for transmitting the rotation of the first shaft to the second shaft, and a number-wheel connected to the second shaft, substantially as set forth.
16. A calculating machine comprising the combination of a shaft, a plurality of keys, means for rotating said shaft in accordance with the value of a selected key, a second shaft, a member movable on the first shaft and controlling by its position the rotation of the second shaft by the first, and a number-wheel connected to the second shaft, substantially as set forth.
17. A calculating machine comprising the combination of a plurality of shafts, key-controlled devices for actuating all of said shafts, setting devices movable on said shafts, and number-wheels actuated by said setting devices, substantially as set forth.
18. A calculating machine comprising the combination of a plurality of shafts, key-controlled devices for actuating all of said shafts in unison, movable setting devices actuated by said shafts, number-wheels actuated by said setting devices, and carrying mechanism between the number-wheels, substantially as set forth.
19. A calculating machine comprising the combination of a plurality of keys for selecting a number, a plurality of setting devices which may be independently positioned simultaneously for setting up another number consisting of a plurality of digits, a plurality of number wheels, and means operated by the depression of said keys for actuating said wheels to cause them to indicate the product of said numbers with the digits of the product in line upon said wheels.
20. A calculating machine comprising the combination of a plurality of shafts, key-controlled devices for actuating all of said shafts in unison in accordance with the value of a selected number, setting devices movable to select a second number consisting of a plurality of digits and to control the actuation of said shafts, and indicating mechanism including number-wheels and carrying mechanism actuated by said shafts for indicating the product of said numbers with said digits in line upon said wheels, substantially as set forth.
21. A calculating machine comprising the combination of setting means which may be independently positioned simultaneously for setting up a number, a plurality of number-wheels, carrying mechanism between said wheels, a plurality of keys, and means actuated by the depression of a key for actuating said wheels to cause them to in-

dicate the product of said number and the number of the key depressed with the digits of the product in line upon said wheels, substantially as set forth.

5. 22. A calculating machine comprising the combination of a driven shaft, a second shaft in alinement therewith, two ratchet wheels on the second shaft, pawls carried by the driven shaft and actuating said ratchets, 10 a pin and slot connection between said second shaft and each of said ratchet wheels, the said slots being oppositely inclined on said shaft, automatically actuated devices for moving said second shaft axially, and a 15 number-wheel driven by one of said ratchet wheels, substantially as set forth.

23. A calculating machine comprising the combination of a plurality of setting means which are independently movable simultaneously for setting up a number, a plurality of keys for selecting another number, a plurality of number-wheels, a movable carriage on which said wheels are mounted, operating means for actuating said wheels 20 to cause them to indicate the product of said numbers, and means for effecting movement of said carriage after each actuation of the operating means, substantially as set forth.

24. A calculating machine comprising the combination of a plurality of setting means which are independently movable simultaneously for setting up a number, a row of 30 keys, a plurality of number-wheels, a movable carriage on which the number-wheels are mounted, means actuated by the depression of a key for actuating a number-wheel an amount dependent on the value of the key depressed and the position of a setting 35 means, and means for effecting movement of said carriage each time a key is depressed, substantially as set forth.

25. A calculating machine comprising the combination of a plurality of setting means which are independently movable simultaneously for setting up a number, a row of 45 keys, a plurality of number-wheels, a movable carriage on which the number-wheels are mounted, means actuated by the depression of any key for operating the number-wheels to cause them to indicate the product of the number set up by said setting means and the value of the depressed key, and means for effecting movement of the carriage each time a key is depressed, substantially as set forth.

26. A calculating machine comprising the combination of a plurality of shafts, a plurality of keys, means for operating said shafts in accordance with the value of depressed keys, gears on said shafts, a plurality of number-wheels actuated by said gears, a carriage on which the number-wheels are mounted, and means for moving the carriage, substantially as set forth.

27. A calculating machine comprising the combination of a plurality of shafts, a row of keys operable to rotate said shafts, setting means movable on said shafts, a plurality of number-wheels actuated by said setting means, a carriage on which the number-wheels are mounted and means for moving the carriage, substantially as set forth.

28. A calculating machine comprising the combination of a plurality of number-wheels, a plurality of actuating mechanisms connected thereto, setting devices independently movable simultaneously for setting up a number consisting of a plurality of digits, said devices controlling the operation of said mechanisms, means for 80 selecting a second number, and operating devices for operating said actuating mechanisms in accordance with the product of said numbers, substantially as set forth.

29. A calculating machine comprising the combination of a plurality of number-wheels, a plurality of actuating mechanisms connected thereto, carrying mechanism between the number-wheels, setting devices for setting up a number consisting of a plurality of digits, said devices controlling the operation of said mechanisms, a plurality of keys, and means actuated by any one of said keys for simultaneously operating a plurality of said actuating mechanisms independently of the carrying mechanisms, substantially as set forth.

30. A calculating machine comprising the combination of a plurality of number-wheels, carrying mechanism between said wheels, a laterally movable carriage on which the wheels are mounted, actuating mechanisms connected to said wheels, a plurality of keys any one of which may be depressed and when so depressed will actuate a plurality of said mechanisms, and a plurality of independently-movable setting devices which may be moved to set up a number and which control the operation of said mechanisms, substantially as set forth.

31. In a calculating machine, the combination of a plurality of shafts and a plurality of number-wheels geared thereto and driven thereby, the gearing between each shaft and its number-wheel including an auxiliary shaft, a gear thereon, means actuated by a number-wheel for moving the auxiliary shaft axially, means including an inclined groove in said shaft and a pin on said gear entering the groove for rotating the gear independently of the auxiliary shaft when the latter is moved axially, and means for returning said auxiliary shaft to its normal position without actuating said gear, substantially as set forth.

32. In a calculating machine, the combination of a plurality of shafts and a plurality of number-wheels geared thereto and

driven thereby, the gearing between each shaft and its number-wheel including an auxiliary shaft, a gear thereon, means actuated by a number-wheel for moving the auxiliary shaft axially, means actuated by the axial movement of the auxiliary shaft in one direction for rotating said gear independently of the auxiliary shaft, and means for returning the auxiliary shaft to its ini-

tial position without actuating said gear, substantially as set forth.

This specification signed and witnessed this 26th day of January, 1912.
